UNITED STATES PATENT OFFICE.

WILLIAM C. METZNER, OF CHICAGO, ILLINOIS.

STOVE-BACK.

SPECIFICATION forming part of Letters Patent No. 369,356, dated September 6, 1887.

Application filed October 15, 1886. Serial No. 216,367. (Model.)

To all whom it may concern:

Be it known that I, WILLIAM C. METZNER, a citizen of the United States, residing at Chicago, in the county of Cook and State of Illinois, have invented certain new and useful Improvements in Stove-Backs; and I do hereby declare the following to be a full, clear, and exact description of the invention, such as will enable others skilled in the art to 10 which it appertains to make and use the same, reference being had to the accompanying drawings, and to letters or figures of reference marked theron, which form a part of this specification.

15 My invention relates to adjustable stove backs or linings which are adapted to be extended or contracted both horizontally and vertically to fit fire-boxes of various sizes.

In the accompanying drawings, Figures 1, 20 2, and 3 are rear elevations of portions of the back. Fig. 4 is a rear elevation of the complete back. Fig. 5 is a front elevation of the complete back. Fig. 6 is a view of the end of the back at the left in Fig. 4. Fig. 7 is a 25 section in line $\alpha\alpha$ of Fig. 5.

A, shown reversed and by itself in Fig. 1, is 30 the main plate, and forms the greater part of the front of the back. This comprises the three parts A', A², and A³. The upper edge 35 of the part A' is curved rearwardly to conform to the fire-box. The portion A² is set forward far enough from the part A' to make an offset, α , deep and wide enough to receive the plate B. At one end of the part A' the 40 portion A³ is set backward to make an offset, α' , to receive the edge of the end lining of the fire-box. This part A³, as shown, does not extend to the bottom of the plate A, but stops at the line of junction between A' and A². It 45 may, however, extend to the lower edge of A².

B is a plate of the same length as the plate A, and wide enough to fill the offset α . The part B⁵ of said plate B, which lies below the part A³, is set backward to correspond with 45 said part A³. At this end of the plate B is an upward extension, B', which overlies the rear of the part A³, such extension being set back from the part B⁵. Said extension is provided with a vertical slot, B², and a bolt, A⁵, passing 50 through said slot and a hole, A⁴, in the part A³, binds said plates together. A web, B³, which is shown as triangular in shape, and

set forward of the part B' in the same plane with B⁵, may extend from the side of the extension B' downwardly to the upper edge of 55 the plate B to strengthen said extension. The two plates A and B together form an even surface to which the remaining plates may be applied.

C is a plate covering the upper portion of 60 the even surface formed by the plates A and B, and extending a short distance beyond said plates at the end opposite the part A³ and the extension B'. When the strengthening web B³ is used, the corner of the plate C is cut off, 65 so that it may fit smoothly with the web. This plate lies in the same plane with the parts A³ and B³. Near its middle it is provided with one or more horizontal slots, C', and a bolt, A⁷, passing through a hole, A⁶, in plate A and one 70 of said slots C', binds the plate C to the plate A.

D is a plate composed of the parts D' and D². The part D' is of proper size to lie in the space over the plate B below plate C, while the part D² is set rearwardly and extends upwardly over the lower portion of the plate C. The part D' of the plate D is provided near 75 its middle with one or more horizontal slots, D³, and a bolt, B⁶, passing through a hole, B⁴, in the plate B and one of the slots D³, binds 80 said plate D to the plate B. The outer end of the part D² of the plate D is provided with a vertical slot, D⁴, and a bolt, C³, passing through a hole, C², in the plate C, binds said 85 plates C and D together.

The plates thus united form a stove-back with practically straight and continuous edges. By loosening the bolts A⁵ and C³ the plates B and D may be lowered to increase the height 90 of the back, and by loosening the bolts A⁷ and B⁶ the plates C and D may be shifted laterally to increase the length of the back.

The plates A and B may be provided with additional holes, A⁵ and B⁴, to receive the bolts A⁷ and B⁶ when the back is to be extended to an extra length.

I am aware that an adjustable stove-back has been heretofore made of four overlying plates, and I do not broadly claim such a back.

I claim as my invention—

In an adjustable stove-back, the combination of the plate A, having the offset α , the plate B, lying in such offset and having the

extension B', through which a bolt binds said plate to the plate A, a plate, C, covering the upper portion of the even surface formed by the plates A and B, and bound to the plate A by a bolt passing through the plates A and C at about the middle of the upper portion of the plate A, and a plate, D, overlying the plates B and C, and bound to the plate B by a bolt at about the middle of the latter plate to and bound to the plate C by a bolt at the end

of the latter and said plate D farthest from the extension B', substantially as shown and described.

In testimony whereof I affix my signature in presence of two witnesses.

WILLIAM C. METZNER.
